CIRCUIT RESTORER

Bryce W. Wyman, Havertown, Pa., assignor to
 General Electric Company, a corporation of
 New York

Application April 6, 1948, Serial No. 19,280

5 Claims. (Cl. 200—89)

1

My invention relates to electric circuit breakers and more particularly to automatically operable reclosing interrupters of the type disclosed and claimed in Patent 2,069,082—Walle, issued January 26, 1937, and assigned to the assignee to whom this application is assigned.

The device disclosed in the above-mentioned patent to Walle provides for a series of time-delayed reclosing operations which cause incremental movement of a lock-out member toward its locking position and which eventually cause the interrupter automatically to become locked in the open circuit position as a result of a predetermined number of successive reclosing operations.

In electric distribution circuits, it is common practice to utilize fuses and automatically operable reclosing interrupters in combination and thereby to achieve optimum protection per dollar of investment in protective apparatus. To this end, it has been found feasible to install fuses on both the source and load sides of one or more reclosers. The time current characteristics of the fuses and reclosers used must be such that the system will be properly coordinated. Experience has shown that it is desirable not only to delay the reclosing operations a predetermined time, as in the above-mentioned patent to Walle, but also to delay certain preselected opening operations of the interrupter where the fault condition is persistent in nature. Under certain circumstances, it may be desirable for the recloser automatically to lock its contacts open after a predetermined number of opening and reclosing operations, while under certain other conditions, it may be desirable for the recloser automatically to lock its contacts closed after a predetermined number of opening and reclosing operations.

My invention is an improvement on application Serial No. 19,249, filed April 6, 1948, Thu-mim, assigned to the same assignee as this application.

It is an object of my invention to provide an automatically operable reclosing circuit interrupter having improved operating characteristics wherein provision is made for time-delayed opening and time-delayed reclosing operations should the fault condition be persistent in nature.

Another object of my invention is the provision of an operating mechanism for automatically operable reclosing circuit interrupters wherein a predetermined number of time-delayed opening and closing operations are utilized to cause the mechanism automatically to lock its contacts in the open circuit position

should the fault condition be persistent in nature.

Still another object of my invention is to provide an operating mechanism for automatically operable reclosing circuit interrupters wherein a member is caused to rotate in response to time-delayed opening and reclosing operations and thereafter to cause the mechanism automatically to lock its contacts in the open circuit position where a persistent fault occurs on the line.

A further object of my invention is the provision of an operating mechanism for automatically operable reclosing circuit interrupters wherein a predetermined number of time-delayed opening and reclosing operations are utilized to cause the mechanism automatically to lock its contacts in the closed circuit position should the fault be persistent thereby to force a system fuse to clear the fault or to cause the fault to burn itself clear.

A still further object of my invention is to provide an automatically operable reclosing circuit interrupter which may readily be converted from the locked-open type to the locked-closed type and vice versa.

Still another object of my invention is to provide a mechanical timing mechanism for automatically operable reclosing devices which affords precise time current characteristics and which is unaffected by changes in ambient conditions.

Still another object of my invention is the provision of automatically operable reclosing circuit interrupters which may be coordinated from recloser to recloser and from recloser to fuses for year-round service.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a schematic representation of the circuit incorporated in an interrupter embodying my invention; Fig. 2 is an elevational view in section of a recloser embodying my invention; Fig. 3 is a view of a portion of the timing mechanism of the device shown in Fig. 2 with the parts shown in the positions which they occupy just after the interrupter has opened substantially instantaneously; Fig. 4 is a view similar to Fig. 3 in which the parts are shown in the positions which they occupy at the beginning of the first time-delayed opening operation; Fig. 5 is a view similar to Figs. 3 and 4 showing the

parts in the positions which they occupy when the interrupter has automatically locked its contacts in the open circuit position; Figs. 6 and 7 show a modification of the timing mechanism embodying my invention wherein provision is made for locking the contacts closed, Fig. 6 showing the mechanism in a position of readiness to begin a series of opening and reclosing operations and Fig. 7 showing the parts in the positions which they occupy when the contacts are locked-closed.

With reference to Fig. 1, the numerals 1 and 2 designate the contacts of the recloser. Contact 1 is connected to schematically represented terminal 6 by a line 4 and movable contact 2 is connected through line 3 to the operating coil 5 which in turn is connected to schematically represented terminal 7 of the interrupter by a line 8. The occurrence of an excessive current on the line will energize the coil 5 sufficiently to cause this coil to elevate contact 2 thereby to interrupt the circuit.

With reference to Fig. 2, the terminal 6 is shown while the terminal 7 does not appear in the drawing. Surrounding the terminal 6 is an insulator 9 which is supported by adapters 10 and 11, bolts 12, and the cover 13. The mechanism is housed in the tank 14, the inner surface of which is covered with insulating material 15. The tank is filled with insulating fluid such as oil to the level indicated. Tank 14 is provided with a flange 16 having a peripheral groove 17 therein. Cover 13 is constructed with a peripheral flange 18. A gasket 19 is inserted into the groove 17 and serves to seal the joint between the flanges 16 and 18. Secured to the cover 13 by welding or other suitable means is a U-shaped supporting structure 20 having downwardly extending side plates, only the rear one of which appears in the cross-sectional view shown in Fig. 2. The lower extremities of the side plates of the supporting structure 20 are provided with outwardly projecting flanges 21 through which bolts 22 extend. Bolts 22 are secured to projections 21 by the nuts 23. Bolts 22 extend downwardly and are secured to the plate 24 by nuts 25. The supporting angle members 26 are secured by bolts 27 to the plate 24. The bolts 27 cooperate with one flange 28 on the angle members 26. Laminated structures 29 and 30 depend from the supporting angles 26 and are secured thereto by any suitable means such as by the rivets 31. Operating coil 5 is supported by laminated structures 29 and 30. Lower supporting angles 32 are secured to the laminated structures by any suitable means such as by the rivets 33. The horizontal metallic plate 34 is secured to the flanges 35 on the supporting angles 32 by bolts 36. Bolts 36 extend downwardly and support the bottom insulating wall 37 of the arcing chamber generally indicated by the numeral 38. Insulating sleeves such as 39 surround the bolts 36, and the arcing chamber housing is held in position by the nuts 40. The side walls of the arcing chamber 38 may constitute a cylinder of insulating material 41. The lower wall 37 of the arcing chamber 38 is provided with blast ports 42 for the expulsion of oil and gas from the chamber 38 into the tank 14 when a circuit interruption takes place between the contacts 1 and 2. Contact 1 is secured to plate 37 by a terminal extension 45 thereof which forms a point of connection for the interval lead 4 to the contact 1. For simplicity, lead 4 is only partially shown in Fig. 2, but, as explained above, lead 4 is connected to the terminal 6 of the re-

closer at a convenient point inside the cover 13. Furthermore, in Fig. 2 the lead 3 is only partially shown but it will be understood from Fig. 1 that this lead connects to one terminal of the operating coil 5 and that the lead 8, which is not shown in Fig. 2, is interposed between the other terminal of the coil 5 and the terminal 7 of the interrupter which terminal is not shown in Fig. 2.

Secured to the plate 34 as by welding is a U-shaped supporting structure 46. Because the view in Fig. 2 is cross-sectional, only the rear one of the downwardly extending cheeks of the U is shown.

For reasons which will become apparent as the description proceeds, the armature 47 must be caused to move upwardly in response to current flow through coil 5 a considerable distance before contacts 1 and 2 are separated. Hence, it is necessary to provide suitable means for delaying the actual separation of the contact 2 until the armature 47 will have moved a substantial distance toward the limit of its upward travel. To this end an over-center toggle device is provided which comprises a lever 48 which is connected to the fixed pivot 49 which is mounted on the cheeks of supporting structure 46. Lever 48 is connected to the movable armature 47 by the pivot 50. A tension spring 51 is connected at either end to the lever 48 by means of a pin 52 and to the contact 2 by a pin 53 respectively. Contact arm 2 is rotatable about the fixed pivot 54 which is carried by the supporting structure 46.

The operation of the contact operating mechanism will now be described. When the armature 47 moves upwardly against the bias of compression type contact closing spring 55, the lever 48 is rotated in the clockwise direction about the fixed pivot 49. From the drawing it will be observed that the extension spring 51 and the contact arm 2 constitute a conventional overcenter spring device so that it will readily be understood that, not until the upwardly moving pin 52 of lever 48 passes beyond its dead center position with respect to pivots 54 and 53, can the contacts 1 and 2 be separated through the agency of the armature's upward pull. Accordingly, this overcenter toggle arrangement provides lost motion means whereby the contacts do not part until the armature has lifted through a major portion of its full upward stroke.

For the purpose of controlling the upward velocity of armature 47 during certain opening operations and also for the purpose of controlling the closing velocity of armature 47 and thereby to establish appropriate time-delayed operations, the timing mechanism generally designated by the numeral 58 is used.

In accordance with my invention an insulating rod 59 is connected to the armature 47 by any suitable means as by the rivets 60 and is movable therewith. The guide link 61 which is pivotally mounted about the fixed pin 62 in the supporting structure 20 is connected to the rod 59 by the pin 63. Link 61, cooperating with lever 48, provides rectilinear vertical movement to the armature and its rod.

For controlling the opening time-delay, I have provided an opening pawl 64 which is pivoted at 65 to its carrier arm 66 which arm in turn is pivoted on and rotatable about the shaft 67, which shaft is mounted upon the supporting structure 20. A torsional spring 76 biases pawl 64 in the clockwise direction about the pivot 65. In the position shown in Fig. 2, pawl 64 is held

out of engagement with the smooth peripheral portion of ratchet wheel 69 by the stop 80 which is mounted on the supporting structure 20. Carrier arm 66 is connected to rod 59 by the curved connecting member 57 which is pivoted to the rod 59 by the pin 63 and to the carrier arm 66 by the pin 68. It will be evident that upward motion of armature 47 with its rod 59 will cause upward motion of the curved link 57. This upward motion will result in clockwise rotation of the carrier arm 66 about the shaft 67. Ratchet wheel 69 is provided with a notched section 70 about its perimeter and also a smooth or unnotched section 71.

For the purpose of governing the velocity of rotation of the ratchet wheel 69 for introducing time-delay at appropriate times, a gear wheel 72 is mounted for rotation on shaft 67 and is secured to the ratchet wheel 69 by rivets or other suitable means.

A pinion 73 mounted on a shaft 74 rotates whenever the gear wheel 72 and the ratchet wheel 69 are caused to rotate. The shaft 74 is secured to the supporting structure 20. Secured to the pinion 73 and rotatable therewith is a timer wheel 75, the entire perimeter of which is notched. An oscillatory verge member 78 is supported on the fixed shaft 79 which in turn is secured to the supporting structure 20. Because the ratchet wheel 69 is connected to the gear wheel 72, it is evident that rotation of ratchet wheel 69 will cause rotation of gear wheel 72, pinion 73, and timer wheel 75, which in turn will result in oscillatory motion of a verge member 78 about its fixed shaft 79 for producing the well-known watch-type escapement. Rotation of the ratchet wheel 69 will thus be controlled in a manner well known in the art. It will also be apparent that, if the pawl 64 happens to be in engagement with the smooth section 71 of the ratchet wheel 69, the armature 47 will be free to move upwardly without impediment. Furthermore, if, after initial rotation of the ratchet wheel 69, pawl 64 engages the toothed section 70, it will be clear that upward movement of armature 47 will be impeded by the oscillatory member 78. Hence, the contacts would be maintained closed for a short time so that a time-delayed opening will be accomplished.

For the purpose of controlling the closing operations of the device, a closing pawl 82 is provided. Pawl 82 is supported on its carrier arm 83 by a pin 84. Pawl 82 is biased in the clockwise direction about pin 84 by a torsional spring 85. Arm 83 is rotatable about the shaft 67 and is interconnected to the rod 59 by the connecting member 86, the latter being pivotally connected to rod 59 by the pin 63 and to the arm 83 by the pin 84. In the contact closed position shown, closing pawl 82 is held out of engagement with the periphery of ratchet wheel 69 by the provision of the fixed stop 81 which is secured to the supporting structure 20.

When armature 47 moves upwardly due to excessive current in coil 5 to produce clockwise rotation of the opening pawl carrier arm 66, it will be apparent that the link 86 also is displaced upwardly at the same time and causes carrier arm 83 to rotate in the counterclockwise direction about the shaft 67. It will be apparent that in this movement the pawl 82 will free-wheel over the notched portion 70 of the ratchet wheel 69 without rotating the ratchet wheel. When the contacts 1 and 2 are fully separated, the mechanism will be free to begin the closing operation.

Pawl 82 now will be biased into engagement with the notched section 70 of the ratchet wheel 69 due to the action of torsional spring 85. Hence, downward motion of armature 47 and the parts associated therewith will be retarded due to the fact that the ratchet wheel 69 and the gear wheel 72 must be rotated against the delaying action of the oscillatory member 78. Hence, the contacts are maintained open for a short time so that a time-delayed closing is accomplished.

For the purpose of causing the ratchet wheel 69 to reset automatically after being rotated from its normal position shown in Fig. 2 for producing one or more time-delayed operations, I have provided a sheave 87, which is secured to and rotatable with the gear 72, and an adjacent co-operating sheave 88 which is biased for clockwise rotation about its fixed shaft 89 by the spring 90, and an interconnecting flexible cord 91 which winds from off the drum 87 and on to the drum 88 during a resetting operation due to the action of spring 90. Shaft 89 is secured to the supporting structure 20.

For the purpose of arresting the opening operation of the mechanism, I have provided a cylindrical buffer 92 which is mounted on the fixed pin 93 which pin is secured to the supporting structure 20. Near the end of the opening operation, the arm 66 encounters buffer 92 and in this manner the momentum of the parts caused by an opening operation is absorbed and the opening motion is arrested without undue shock.

It will be understood that my invention could be adapted to perform, within limits, a relatively wide range of opening and closing operations wherein certain of these operations would be time-delayed and wherein certain others would be made to occur substantially instantaneously. For persistent faults, the particular embodiment of my invention described above and shown in Figs. 1 and 2 is adapted to perform a first instantaneous opening operation followed by a time-delayed closing operation, a second instantaneous opening operation followed by a time-delayed closing operation, a third opening operation which is time-delayed followed by a third time-delayed closing operation and a fourth opening operation which is time-delayed followed by a final lock-out operation.

Assuming that the recloser is in the closed position as shown in Fig. 2, a fault on the line will cause an excessive current to flow through the interrupter circuit shown in Fig. 1. This excessive current will cause the operating coil 5 to elevate the armature 47.

This upward motion of armature 47 will cause the opening pawl carrier arm 66 to rotate clockwise about the shaft 67 and will also cause the closing pawl arm 83 to rotate counterclockwise about the shaft 67. When the upwardly moving mechanism parts reach a point near the limit of opening movement, the contact arm 2 will move out of engagement with the contact 1 for drawing and interrupting an arc, and the above-mentioned parts will then assume the positions shown in Fig. 3. Pawl 64 will have ridden over the smooth portion 71 of the ratchet wheel 69 and the opening pawl 82 will have free-wheeled over the notched section 70 of the ratchet wheel 69 without impediment and the opening operation will have occurred substantially instantaneously. Once the contacts 1 and 2 have separated, there is no current in coil 5 and, hence, the mechanism is freed from upward force and may return downward by gravity and spring bias toward the con-

tact closed position. This contact closing operation will be with time-delay as already explained because the closing pawl 82 will now be in engagement with the notched section 70 of the ratchet wheel 69 and, hence, will cause rotation of the ratchet wheel 69, gear wheel 72, and through pinion 73 and timer wheel 75 which latter will cause verge member 78 to oscillate. The delayed portion of the closing operation terminates when the closing pawl 82 comes into engagement with the stop 81, for the pawl 82 is moved thereby out of engagement with the periphery of the ratchet wheel 69. Immediately thereafter, the contact arm 2 snaps into closed circuit position, the spring 51 having moved back into its initial overcenter region.

Should the fault be persistent in nature, the contacts will be opened again substantially instantaneously because the smooth portion 71 of the ratchet wheel 69 is not entirely rotated out from under the opening pawl 64 by the first delayed reclosure. The following or second reclosing operation will be with time-delay because the pawl 82 in its upper position will still be opposite the notched portion of ratchet wheel 69.

At the termination of the second reclosure the parts will then occupy the positions shown in Fig. 4 and the ensuing or third opening operation will be with time-delay because the opening pawl 64 will now engage the advanced toothed section 70 of the ratchet wheel 69 as soon as the pawl moves away from its stop pin 80. The next subsequent reclosing operation, which is the third, will also be with time-delay, for the closing pawl 82 engages the toothed portion as in the earlier reclosures.

The fourth opening operation will also be with time-delay, as in the third opening explained above. Upon completion of this fourth opening operation, the mechanism will automatically lock the contacts in the open circuit position. To this end, I have provided a hook-type latch 94 which is pivotally hung from the pin 95 which is secured to the supporting structure 20. The lower portion of latch 94 is curved or hook-shaped for performing its holding function. Indicated at 97 is a crankpin which is overhung from the forward surface of the ratchet wheel 69. Pin 97 projects outwardly from the forward face of ratchet wheel 69 far enough to engage the arm 66 but not far enough to interfere with motion of the arm 83. Intermittent clockwise rotation of the ratchet wheel 69 caused by successive delayed opening and closing operations during a persistent fault eventually will advance the pin 97 into or beyond the hooked section 96 of the arm 94. From Fig. 2 it will be clear that the arm 94 first will be swung to the left by the pin 97 engaging the surface 98 of the arm 94 before it rides over the surface 98 and into the hooked portion 96 of the arm 94. Once it has passed into the hooked section 96 of the arm 94, the pin will no longer be free to move back out of the hooked section 96 of the arm 94 and pin 97, furthermore, will engage the carrier arm 66 as it rebounds from the buffer 92 so as to hold that arm in an elevated position as shown in Fig. 5. Otherwise stated, both the ratchet wheel 69 and carrier arm 66 are now rendered incapable of rotating back in the counterclockwise direction. Accordingly, the mechanism cannot reset and the contacts will be locked-open.

It will be evident that the particular position chosen for the pin 97 on the ratchet wheel 69 should be such that the pin 97 will have ad-

vanced to its holding position inside the hooked portion 96 of the arm 94 whenever the mechanism will have completed the desired number of time-delayed opening and closing operations so that the armature 47 and parts associated therewith will be prevented from moving downwardly under the urge of the biasing spring 55 and the pull of gravity. The cooperating parts in the particular embodiment of my invention described above are so proportioned that the contacts become locked open after two instantaneous opening operations followed by two time-delayed opening operations, all the intervening reclosures being with time delay.

In order to close the contacts after the interrupter has automatically locked its contacts in the open position, it is only necessary to rotate the arm 94 in the clockwise direction about the shaft 95 thereby to unlatch the crankpin 97. For this purpose the shaft 95 is extended through one of the side plates of the supporting structure 20 and through the wall of the cover 13 so that a portion of the shaft 95 projects outside the cover 13. To this exteriorly extending portion of the shaft 95 there is keyed a manual crank 99 which has an opening 99' at its outer end. To close the contacts, an operator merely inserts a switch hook into the opening 99' of the arm 99 and pulls downwardly. This operation releases the pin 97 from the hooked portion 96 of the arm 94, and the armature 47 and parts associated therewith then are free to move downwardly to the contact closed position. Coincident with this manual closing operation, opening pawl 64 and closing pawl 82 encounter their holdout pins 80 and 81, respectively, thereby moving them out of contact with the ratchet wheel periphery so that the mechanism would reset under the action of spring 80 and the winding mechanism associated therewith. This resetting movement is slow because the verge member 78 retards the otherwise free movement of the gear train irrespective of the direction of rotation.

For manually opening and closing the contacts, an external crank arm 100 is provided which is pivotally mounted upon the pin 101 which is secured to the side walls of the cover 13. Arm 100 has an opening 102 at its right-hand end. An internal crank arm 103 is secured to the left-hand end of crank arm 100 and, hence, is movable therewith. A link 104 is pivotally connected at 105 to the internal arm 103. A pin 106 is mounted on the closing pawl carrier arm 83 and is slidable within a slot 107 in the lower part of link 104. The lost motion slot 107 permits the manual bell crank to idle when the mechanism is operating automatically.

In order to open the contacts, an operator inserts a switch hook into the opening 102 of the arm 100 and pulls downwardly. This action cranks the pin 105 upwardly thereby elevating the rod 59 and armature 47 through the link 86, and the contact 2 accordingly snaps open. The contact will be held in the open position because pin 105 will have rotated about the pin 101 to an over-center position with respect to pin 101.

In order to close the contacts after they have been manually opened, it is only necessary for the operator to insert the switch hook into the opening 102 in the arm 100 and to push it upwardly back to the position shown. Although this manual closing action may be done smartly because of the lost motion slot 107, the actual

closing operation will be attended with time-delay because the closing pawl 82 will have engaged the ratchet wheel just as in the first automatic opening operation.

The above-described mechanism may be simply and easily converted to a device which is capable of automatically locking the contacts in the closed position after a predetermined number of opening and reclosing operations by modifying the mechanism as shown in Figs. 6 and 7. To this end, I provide means which becomes effective for preventing upward movement of the carrier arm 66 from its "down" position at the termination of the reclosing cycle thereby to render the armature impotent to respond to the energized coil. In other words, whereas arm 66 is held up for locking the contacts open, this arm is held down for locking them closed. For achieving this purpose, the supporting member 110 is secured to the fixed structure 20 by any suitable means and a push rod 111 is slidably mounted therethrough in an opening therein. A compressional return spring 112 bears against a surface of the member 110 and against the enlarged end portion 113 of the rod 111. A cam 114 is eccentrically mounted on and secured to the shaft 74 for rotation with the ratchet wheel 75 which, as explained above, is secured to and rotatable with the pinion 73. In Figs. 6 and 7 the shaft 74 is shown to the right of the ratchet wheel 69 while in Fig. 2 the shaft 74 and parts associated therewith are shown to the left of the ratchet wheel. It will be understood that the location of these parts is not critical and that the parts could function equally well in either position. The supporting shaft 115 is secured to the supporting structure 20 and has mounted pivotally thereon the hook catch member 116. The member 116 is rotatable about the shaft 115 and has a hooked portion 117 constituting a catch at its upper right-hand end. The rod 111 is constructed with an enlarged threaded portion 118 at its lower left-hand end. The nut 119 affords a bearing surface for the compression spring 120. The spring 120 also bears against a laterally projecting surface 121 of the catch 116, the nut 122 providing adjustment for holding the catch 116 in its proper place with respect to the arm 66. In other words, the catch 116 is resiliently coupled to its operating push rod 111.

In Fig. 6 the parts are shown with the breaker occupying its closed position. In this arrangement, no provision for delayed opening is contemplated, for the opening pawl 64 has been omitted from the carrier arm 66. Accordingly, only a predetermined sequence of time-delayed reclosures contributes to the advancement of the ratchet wheel 69 from the position shown in Fig. 6 to that shown in Fig. 7. This rotation of ratchet wheel 69 will be accompanied by rotation of pinion 73 (of Fig. 1) and the associated eccentric cam 114. With the parts shown in the closed position, as in Fig. 6, the arm 66 is free to move about the shaft 67 without interference by the hooked end 117 of the arm 116. When the eccentric cam 114 has revolved from the position shown in Fig. 6 to that shown in Fig. 7, the rod 111 will have been moved downwardly and to the left against the urge of its return spring 112 due to the engagement of eccentric cam 114 and the enlarged portion 113 of the rod 111. This motion of the rod 111 will rotate the catch 116 in the clockwise direction about the fixed shaft 115 and, after a predetermined angular displacement of ratchet wheel 69, the hooked portion 117

of the catch 116 will be in a position effectively to block clockwise rotation of the arm 66 as shown in Fig. 7. The resilient connection afforded by spring 120 allows the arm 66 to fall into catching relation in the event that catch 116 has moved over while the arm 66 happens to be moving in the region above the catch 116. Thus the armature 47 will be prevented from moving upwardly even though an excessively high current may be flowing through the interrupter. The fault will then be forced to either burn itself out, to blow an appropriate fuse, or to trip the station breaker.

While the arm 66 cannot rotate in the clockwise direction about the shaft 67 during a lock-closed operation, the ratchet wheel 69, which has been freed to back-track by the pawl 82 striking its stop pin 84, will thereupon be rotated back to the reset position shown in Fig. 6 by the action of spring 90 and apparatus associated therewith so that the mechanism will be in readiness to perform a subsequent series of operations within a fairly short time after the device has automatically locked in the closed circuit position. Upon clearance of the fault or the opening of a backup fuse or breaker, the upward force on the mechanism parts will be removed so that the arm 66 will fall back against its stop 123, thereby permitting the catch 116 freedom to swing back to its normal position, as in Fig. 6, in accordance with the resetting operation.

At any time during the reclosing cycle after the occurrence of a fault condition, the mechanism will automatically reset if the fault is removed, either by burning itself out or by being cleared by a fuse or the station breaker or another recloser.

While I have shown and described particular embodiments of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patent of the United States is:

1. In an electric circuit reclosing device, relatively movable interrupting contacts, electromagnetic means having a coil and an armature, said armature being operably related by a lost motion connection with a movable one of said contacts and being responsive to predetermined fault current in said coil for imparting opening movement to said movable one of said contacts, a timing mechanism including a ratchet wheel having a smooth and notched portion about its periphery, an opening pawl normally disposed to engage a smooth portion of said ratchet wheel, a connecting member directly attaching said pawl with said armature, said pawl and armature being movable in response to predetermined energization of said coil, means for closing said contacts, a closing pawl, a second connecting member directly connecting said armature with said closing pawl, said closing pawl being engageable with a notched portion of said ratchet wheel after completion of a circuit interrupting operation to delay closing of said contacts, a notched portion of said ratchet wheel being engageable by said opening pawl after a predetermined advancement of said ratchet wheel to render said opening pawl effective to delay opening movement of said armature.
2. In an electric circuit reclosing device, rela-

tively movable interrupting contacts, electromagnetic means having a coil and an armature, said armature being operably related by a lost motion connection with a movable one of said contacts and being responsive to predetermined fault current in said coil for imparting opening movement to said movable one of said contacts, a timing mechanism including a ratchet wheel, an opening pawl, a connecting member directly attaching said pawl with said armature, said pawl and armature being movable in response to predetermined energization of said coil, said ratchet wheel being engageable by said opening pawl to delay an opening movement of said armature and of said contacts, means for closing said contacts, a closing pawl, and a second connecting member directly connecting said armature with said closing pawl, said closing pawl being arranged to engage said ratchet wheel after completion of a circuit interrupting operation to delay closing movement of said armature and of said contacts, said connecting members being pivotally connected to said armature at a common point.

3. In an electric circuit reclosing device, relatively movable interrupting contacts, electromagnetic means having a coil and an armature, said armature being operably related with a movable one of said contacts by a lost motion connection and being responsive to predetermined fault current in said coil for imparting opening movement to said movable one of said contacts, a timing mechanism including a ratchet wheel having a smooth and a notched portion about its periphery, an opening pawl normally disposed to engage said smooth portion of said ratchet wheel, a connecting member directly attaching said opening pawl with said armature, said opening pawl and armature being movable in response to predetermined energization of said coil, means for closing said contacts, a closing pawl, and a second connecting member directly connecting said armature with said closing pawl, said closing pawl being arranged to engage said ratchet wheel after completion of a circuit interrupting operation to delay closing movement of said armature and of said contacts.

4. In an electric circuit reclosing device, relatively movable interrupting contacts, electromagnetic means having a coil and an armature, said armature being operably related with a movable one of said contacts by a lost motion connection and being responsive to predetermined fault current in said coil for imparting opening movement to said movable one of said contacts, a timing mechanism including a ratchet wheel, an opening pawl, a connecting member directly at-

taching said pawl with said armature, said pawl and armature being movable in response to predetermined energization of said coil, said ratchet wheel being engageable by said opening pawl to delay an opening movement of said armature and of said contacts, means for closing said contacts, a closing pawl, and a second connecting member directly attaching said armature with said closing pawl, said closing pawl being engageable with said ratchet wheel after completion of a circuit interrupting operation to delay closing of said contacts.

5. In an electric circuit reclosing device, relatively movable interrupting contacts, electromagnetic means having a coil and an armature, said armature being operably related with a movable one of said contacts by a lost motion toggle connection having a normally overcenter position corresponding to the closed position of said movable one of said contacts and being responsive to predetermined fault current in said coil for opening said movable one of said contacts, said lost motion toggle connection being effective to cause said contacts to remain closed until after predetermined opening movement of said armature, a timing mechanism including a ratchet wheel, an opening pawl, a connecting member directly attaching said pawl with said armature, said pawl and armature being movable in response to predetermined energization of said coil, said ratchet wheel being engageable by said opening pawl to delay an opening movement of said armature thereby to prevent operation of said toggle and opening of said movable one of said contacts until a major portion of the opening movement of said armature is completed, means for closing said contacts, a closing pawl, a second connecting member directly attaching said armature with said closing pawl, said closing pawl being engageable with said ratchet wheel during a closing movement of said armature to delay closing movement thereof and of said movable one of said contacts until said toggle is moved over center.

BRYCE W. WYMAN.
